F. W. PENDERGAST.
WIND AND WATER MOTOR.
APPLICATION FILED SEPT. 18, 1918.

1,306,311.

Patented June 10, 1919.

THE NORRIS PETERS CO., PHOTO-LITHO., WASHINGTON, D. C.

UNITED STATES PATENT OFFICE.

FREDERICK W. PENDERGAST, OF CAMBRIDGE, MASSACHUSETTS.

WIND AND WATER MOTOR.

1,306,311.

Specification of Letters Patent. Patented June 10, 1919.

Application filed September 18, 1918. Serial No. 254,654.

To all whom it may concern:

Be it known that I, FREDERICK W. PENDERGAST, a citizen of the United States, residing at Cambridge, in the county of 5 Middlesex and State of Massachusetts, have invented new and useful Improvements in Wind and Water Motors, of which the following is a specification.

This invention, as illustrated by the drawings hereinafter referred to, is embodied in a wind mill or motor, although it may be embodied in a motor adapted to be driven by water in motion.

The invention relates to a motor of the character stated, comprising a rotary wheel frame, having radial arms, and vanes or blades pivoted to the arms and adapted to be maintained substantially in alinement with each other at one side of the axis of 20 the wheel to present a substantially continuous front to an impelling current, and to automatically swing edgewise to the impelling current at the opposite side of the axis.

25 The chief object of the invention is to provide automatic governing means for permitting the vanes to yield to excessive pressure, and thus compensate for variations in the pressure of the wind or other impelling element. The invention is embodied in the improvements which I will now proceed to describe and claim.

Of the accompanying drawings, forming part of this specification:

35 Figure 1 is a side elevation of a wind motor embodying the invention.

Fig. 2 is a section on line 2—2 of Fig. 1, and a plan view of parts below said line.

Fig. 3 is a section on line 3—3 of Fig. 1.

40 Fig. 4 is an enlargement of a portion of Fig. 2.

Fig. 5 is an enlargement of a portion of Fig. 1.

45 Fig. 6 is a view similar to a portion of Fig. 2, showing the minimum displacement of the vanes by wind pressure.

Figs. 7, 8 and 9 are fragmentary perspective views illustrating features shown by the preceding figures.

50 Fig. 10 is a fragmentary perspective view illustrating a different form of governor.

Fig. 11 is a fragmentary sectional view illustrating a portion of the structure shown by Fig. 10.

The same reference characters indicate 55 the same parts in all of the figures.

In the drawings 12 represents a base or tower, to which is secured a vertical spindle 13. Mounted to rotate on the vertical axis formed by the spindle is a wheel frame 60 which includes spaced-apart spiders having hubs 15 journaled on the spindle, arms 14 radiating from the hubs, and outer standards 16 perpendicular to the arms and rigidly connecting their outer ends. The 65 frame also preferably includes inner standards 17 connecting the hubs 15, the spiders being spaced apart by the outer and inner standards. The arms 14 are arranged in pairs, each pair including an arm on the 70 upper spider and an arm on the lower spider.

Extending between the arms 14 and pivoted thereto at 18 to swing on vertical axes are blades or vanes 19 arranged, as here 75 shown, in four series, each vane being pivoted at one edge. There is a series of vanes extending between each pair of arms 14.

Associated with each series of vanes is a 80 governor, connected with the frame and bearing yieldingly on the vanes, said governor being adapted normally to hold the vanes in alinement with each other and to yield and permit the vanes to be opened or 85 moved out of alinement by fluid pressure exerted upon them. Each governor includes a plurality of resilient metal rods or springs 20, connected with the arms 14 of the lower spider, and projecting upwardly 90 therefrom, the upper ends of the rods 20 being connected by a cross-bar 21 bearing on the vanes 19. The lower ends of the rods 20 are rigidly confined on the arms of the lower spider, their upper ends and the cross-bar 95 21 being adapted to yield to pressure exerted on the vanes.

By reference to Fig. 2 it will be seen that, when wind pressure in the direction of the arrow X is exerted on the wheel, the vanes 100 at one side of the axis of the wheel are pressed against the corresponding governor, the vanes being normally maintained substantially in alinement with each other by the governor, and adapted to be opened or 105 moved out of alinement with each other by the yielding of the governor. The rotation of the wheel being in the direction indicated

by the arrow Y (Fig. 2), the vanes at the opposite side of the axis, these vanes being behind the corresponding governor, are permitted to stand edgewise to the wind, as shown by dotted lines in Fig. 2.

I prefer to provide means for displacing the governors to permit a maximum opening of the vanes, and thus enable the rotation of the wheel to be arrested without undue resistance. To this end I attach the resilient rods 20 to slides 23, which are or may be rods adapted to slide endwise and turn in bearings 24 on the arms 14 of the lower spider. Said slides are provided with studs 25, which are preferably prolongations of the rods 20, as best shown by Figs. 7 and 8. These studs bear on oblique abutments 26 attached to the arms 14. Each slide 23 is normally held in the position shown by Fig. 7 by a spring 27 fixed at 28 to the slide and at 29 to one of the bearings 24, the arrangement being such that when the spring 27 is free to act, it holds the stud 25 against an outer portion of the abutment 26, so that the abutment and stud confine the rod 20 and prevent it from swinging loosely, the only movement of the rod being that due to its flexure by the pressure of the vanes against the governor. When the slide 23 is moved to the position shown by Fig. 8, the spring 27 yields, and the stud 25 moves to an inner portion of the abutment 26, so that the rod 20 is permitted to swing bodily from the position shown by Fig. 7 to that shown by Fig. 8, thus permitting a maximum displacement or opening of the vanes.

The slide 23 is provided at its inner end with a lug 30, which engages the inner side of a band brake 31, one end of which is connected at 32 (Fig. 2) with the base 12. Said brake partially surrounds a grooved pulley 33, attached to one of the hubs 15, the free end of the brake being connected with a pivoted lever 34 adapted to exert tension on the brake and set the same upon the pulley 33.

It will now be seen that, when the brake is set to stop the wheel, the slide 23 is moved endwise to displace the governor. The pulley 33 is provided with orifices 35 into which the lugs 30 project.

Figs. 10 and 11 illustrate a governor adapted to permit a wider opening of the vanes than the form of governor shown in the preceding figures, said governor including rods 20^a connected by a cross-bar 21^a, the lower ends of the rods being fixed to the slide 23, the construction being otherwise substantially as above described.

Power may be transmitted from the wheel through a gear 37 attached to the pulley 33 and a similar gear or pinion 38 mounted on a shaft 39.

When the invention is embodied in a water motor, the governors may be carried by the arms of the upper spider, said arms, the

brake pulley 33, and the band brake 31 being located above the vanes and above the surface of a stream of water in which the main portions of the vanes are immersed.

70

I claim:

1. A motor of the character stated, comprising a rotary wheel frame rotatable on a vertical axis, and including rigidly connected spaced-apart spiders having radial arms arranged in pairs, vanes pivoted to said arms to swing on vertical axes, and extending between the spiders, there being a series of vanes extending between the arms of each pair, and governors connected with the frame and bearing yielding on the vanes, there being a governor for each series of vanes, said governors being adapted normally to hold the vanes in substantial alinement with each other and to yield to permit the vanes to be opened or moved out of alinement by fluid pressure.

2. A motor of the character stated, comprising a rotary wheel frame including rigidly connected spaced-apart spiders having radial arms, vanes pivoted to said arms and extending between the spiders, resilient rods connected with the arms of one of the spiders and projecting therefrom beside the vanes, said rods having cross-bars at their outer ends held yielding against the vanes by the rods, said rods and cross-bars constituting spring-yielding governors adapted normally to hold the vanes in substantial alinement with each other and to permit the vanes to be moved out of alinement by wind pressure.

3. A motor of the character stated, comprising a rotary wheel frame including rigidly connected spaced-apart spiders having radial arms, vanes pivoted to said arms and extending between the spiders, governors connected with the frame and bearing yielding on the vanes, said governors being adapted normally to hold the vanes in substantial alinement with each other and to yield to permit the vanes to be opened or moved out of alinement by fluid pressure, and means for displacing said governors to permit a maximum opening of the vanes.

4. A motor of the character stated, comprising a rotary wheel frame including rigidly connected spaced-apart spiders having radial arms, vanes pivoted to said arms and extending between the spiders, slides movable on the arms of one of the spiders, said arms being provided with oblique abutments, governors including resilient rods attached to said slides and projecting beside the vanes, said rods having cross-bars at their outer ends held yielding against the vanes by the rods, the slides being provided with studs projecting oppositely from the rods and in sliding contact with said abutments, and springs acting on the slides to hold said studs against the abutments, the

130

arrangement being such that, when the slides are held in their normal positions by the springs, the abutments and studs hold the governors in their operative positions, and 5 when the slides are moved from their normal positions the abutments and studs permit the displacement of the governors and a maximum opening of the vanes.

5. A motor of the character stated, comprising a base, a band brake secured at one end to the base, means on the base for exerting tension on the band brake, a wheel frame mounted to rotate on the spindle and having a pulley engageable by the brake, 10 said frame including rigidly connected spaced-apart spiders having radial arms, vanes pivoted to said arms, slides movable 15 on the arms of one of the spiders and having

ears engaged by the band brake, governors carried by the slides and bearing yieldingly 20 on the vanes, said slides and governors being movable by the brake when the latter is set, and means for normally maintaining the governors in their operative positions, said means being rendered inoperative by the setting of the brake so that the displacement of the governors and a maximum opening of 25 the vanes is permitted when the brake is set.

In testimony whereof I have affixed my 30 signature.
